Application filed November 12, 1884. Serial No. 147,740. Term of patent 14 years.

To all whom it may concern:

Be it known that I, EDWARD S. PECK, (assignor to the NEW YORK STATIONERY AND ENVELOPE COMPANY,) of Brooklyn, Kings county, New York, have invented and produced a new and original Design for a Doll for Children, of which the following is a specification.

The nature of my design is clearly shown in the accompanying photographic impression, to which reference is made; and it consists of a doll made to represent Santa Claus or St. Nicholas, having a drum depending from one arm,

while above the shoulder extends a projection representing the American flag.

Having now described my invention, I claim as new—

The design for a doll, consisting of a figure representation of Santa Claus or St. Nicholas having one hand full of toys, while in the other is shown a United States flag, substantially as set forth and shown.
